UNITED STATES PATENT OFFICE

ELDEN R. PICKARD AND EDWIN C. PLATTS, OF EUGENE, OREGON.

SOCKET.

1,359,424.

Specification of Letters Patent. Patented Nov. 16, 1920.

Application filed January 7, 1920. Serial No. 349,911.

To all whom it may concern:

Be it known that we, ELDEN R. PICKARD and EDWIN C. PLATTS, citizens of the United States, residing at Eugene, in the county of Lane and State of Oregon, have invented certain new and useful Improvements in Sockets; and we do hereby declare the following to be a full, clear, and exact description of the invention, such as will enable others skilled in the art to which it appertains to make and use the same.

This invention relates to improvements in electric light sockets and the principal object of the invention resides in the provision of a socket having an automatic overload circuit breaker arranged therein by means of which the circuit will be broken through said socket when an instrument requiring more than a predetermined amount of current is connected with said socket, thereby avoiding injury to the wiring within the building and also for protecting the fuses.

Another object of the invention is to provide a device which is particularly adapted for use in hotels and the like, in order to prevent a person from connecting irons and other heating apparatus with the socket which apparatus requires more than a predetermined quantity of power thus avoiding the possibility of the running up of the power bill owing to the excess consumption of current.

A further object of the invention resides in the provision of a novel form of overload circuit breaker which is compactly constructed and capable of being placed within a lamp socket without materially changing the size and shape of the same.

With these and other objects in view, the invention consists in the novel combination and arrangement of parts which will be fully set forth in the following specification and accompanying drawings, in which:

Figure 1 is a vertical sectional view through a lamp socket constructed in accordance with this invention,

Fig. 2 is a similar view taken at right angles to Fig. 1,

Fig. 3 is a fragmentary vertical-sectional view through the lamp socket showing a lamp in place and illustrating the device as it would appear under normal circumstances,

Fig. 4 is a view similar to Fig. 3 showing the sliding core of the solenoid moved up-

wardly and illustrating the latch released prior to the breaking of the circuit,

Fig. 5 is a view similar to Fig. 4 showing the device after the circuit has been broken,

Fig. 6 is a bottom plan view of the socket,

Fig. 7 is a horizontal section taken on line 7-7 of Fig. 5,

Fig. 8 is a detail perspective view of the bridging contact, and

Fig. 9 is a detail perspective view of the armature of the solenoid which is slidably mounted on the stem of the bridging contact.

Referring to the drawings, 1 designates the outer shell of the socket provided with the usual insulating lining 2. The lower end of the shell is reduced and has fitted therein a threaded sleeve 3 into which the base of a lamp bulb is adapted to be threaded. A cap 4 fits the upper end of the socket and is provided with the usual insulating bushing 5 through which the feed wires 5^a and 5^b pass. Fitted in the upper end of the shell are the usual insulating blocks 6 and 6^a carrying a key 6^b for manipulating the movable contact 7 of a well known type of key switch by which the current is switched on and off of the socket. The wire 5^b is connected to the upper stationary contact 7^a of the key switch by a bolt 7^b. A binding post 8 is attached to the block 6 and secured to this binding post is one terminal of the feed wire 5^a while a similar wire 9 is connected to said binding post and leads to a contact screw 10 carried by the threaded shell 3 for establishing electrical communication between the feed wire and shell. In the inner end of the shell 3 is an insulator 11 supporting the central contact 12 of the lamp socket and the contacts 13 and 14 in connection with which the bridging contact co-operates.

The contact 14 is connected to the central contact 12 by means of a bolt 15 which serves to hold the contacts in place. The contact 13 is held in position by a screw 16 which also serves as a connector for one terminal of the wire 17 which is connected to one terminal of the solenoid coil as will be more fully hereinafter described.

A central aperture 18 is formed in the insulator 11 and an aperture 19 is formed in the contact plate 12 in axial alignment with the aperture 18 and is of greater diameter to receive the head of the sliding rod which will be hereinafter more fully described.

Supported within the shell 1 intermediate its upper and lower ends, is a spool 20 having a hollow core in which a sliding core designated generally by the numeral 21 is 5 operatively mounted. This sliding core is best illustrated in Fig. 9 and comprises a cylinder 22 of a relatively soft iron having formed therein a central bore 23. A longitudinal slot 24 is formed in the cylinder 22 and 10 communicates with the bore 23. This slot extends substantially one-half the length of the cylinder and is provided at its lower end with an inclined wall 25 which is slotted as at 26 to accommodate the latch pin of the 15 plunger locking latch which will be more fully hereinafter described. Formed at the lower terminal of the spool is a latch guide 27 in which a latch 30 is slidably mounted. A spring 31 normally urges said latch for- 20 wardly toward the plunger. The latch is provided with an inclined cam face 32 which is adapted to be engaged by the inclined face 25 of the sliding core 21 when said core is moved upwardly into the core of the 25 magnet which consists of the spool 20 having wound thereon a suitable magnet winding. It will be seen that in the upward movement of the armature 21 the latch will be moved outwardly against the compres- 30 sion of the spring 31 and thereby release the plunger which will be more fully hereinafter described.

The plunger above referred to is, designated generally by the numeral 34 and com- 35 prises a tubular stem 35 formed at its upper end with a head 36 and at its lower end with a bridging contact 37 which coöperates with the contacts 13 and 14 in completing the circuit through the socket. A pair of diamet- 40 rically opposed slots 38 are formed in the head 36 and are adapted to accommodate guide pins 39 carried by the spool 20. It will be seen that any possibility of the plunger 34 turning so as to cause the bridging con- 45 tact to move out of proper alinement with the contacts 13 and 14 is eliminated. The tubular stem 35 is formed adjacent its upper end with a longitudinal slot 40 through which a transverse guide pin 41 carried by 50 the sliding rod extends in order to prevent the rod from turning, this pin also assisting in the resetting of the device. An aperture 42 is formed in the tubular stem 35 intermediate its upper and lower ends and is 55 adapted to receive the pin 33 of the latch member 30 when the stem is in normal position in order to hold the same against accidental movement.

Slidable through the hollow stem 35 is a 60 rod 43 having a head 44 at its lower end and a head 45 at the upper end. A compression coil spring 46 is interposed between the under side of the insulator 11 and the upper side of the head 44 so as to normally move 65 said stem downwardly into position shown

in Figs. 1 and 2. A retractile coil spring 47 is attached to the under side of the head 45 and to the upper side of the bottom wall of the hollow head 36 so that when the rod 43 moves upwardly upon the positioning of the lamp base within the socket as illustrated in Figs. 3, 4, and 5, the spring 47 will be tensioned thereby tending to move the plunger 34 upwardly to cause the contact 37 to disengage the contacts 12 and 14. 70 The magnet winding of the solenoid has one terminal connected by a wire 48 to stationary contact 7^a of the key switch while the opposite terminal is connected by the wire 17 to the binding screws 16 and contact 13. 80 Under normal conditions when a lamp bulb is screwed into place it will be apparent that its base will engage the head 44 and move the rod 43 upwardly against the tension of the spring 46, and the tension of the spring 85 47 until the lamp base engages the central contact 12. Upon closing the key switch the current will flow through the wires 5^a and 9 into the shell 3 and then through the apparatus connected to the socket and back 90 to the central contact 12 and the contacts 14, 37 and 13, into coil from whence it will pass out through the wire 48 and key switch to the wire 5^b. In the event that an instrument which takes too much current is attached to the socket the magnetism in the coil will exceed that ordinarily produced thereby energizing the coil to such an extent as to pull the core 21 inwardly thus causing the cam face 32 100 to engage the cam face 32 of the latch 30 and move the latch so that the lock pin 33 disengages the wall of the opening 42. The plunger 35, head 36 and contact 37 will be free to move upwardly under the influence of the spring 47 thereby 105 causing the contact 37 to disengage the contacts 13 and 14 and break the circuit through the socket. After the circuit has been broken in the socket it is automatically reset upon the removal of the attachment 110 plug, by the spring 46 exerting downward pressure on the head 44 which will cause the pin 41 to engage the lower wall of the slot 40 formed in the plunger 35; thus moving the same downwardly until the contacts 13 115 and 14 are bridged by the contact 37 at which time the latch 30 will move under the influence of the spring 31 so as to cause the latch pin 33 to engage in the opening 42 and thus lock the device in set position 120 for reuse.

From the foregoing it will be apparent that an attempt to draw more current through the socket than the device is set for will operate to throw off the current and thereby avoid any possibility of injuring the wiring.

While in the foregoing there has been shown and described the preferred embodiment of this invention, it is to be understood 130

that such changes may be made in the combination and arrangement of parts as will fall within the spirit and scope of the appended claims.

5 Having thus described our invention, what we claim is:—

1. In an electric light socket, a shell, a feed wire connected to said shell, a solenoid, a second feed wire connected to one terminal of said solenoid, a support of insulation, a contact carried by said support, a wire connecting the other terminal of said solenoid to said contact, a central contact carried by said support, a switch connecting said contacts, a hollow plunger connected to said switch and passing within the bore of the solenoid, a rod passing through said plunger and extending beyond the central contact, a spring connected to said rod and plunger 20 and adapted to be tensioned by the movement of the rod in one direction with relation to the plunger, a latch engaging said plunger to hold it against movement to permit said rod to be moved with relation to the plunger by and during the insertion of the lamp plug within the shell, and a core for the solenoid slidably mounted in said plunger and adapted when moved by the solenoid to move said latch out of engagement with the plunger, said spring being adapted to move the switch blade out of contact with said contacts on the withdrawal of the latch from engagement with the plunger.
2. An electric socket including a shell, a feed wire connected to said shell, a solenoid within the shell, a second feed wire connected to one terminal of said solenoid, a pair of spaced contacts, a wire connecting one of the contacts to the other terminal of said solenoid, a switch member engaging said contacts, means operable on the insertion of a plug into the socket to move said switch member out of engagement with said contacts, a latch engaging said switch member and a core for the solenoid adapted when moved by the solenoid to move the latch out of engagement with said switch member so as to permit said means to move the switch member out of engagement with said contacts. 35
3. The construction set forth in claim 1, and a second spring mounted on said rod for normally retaining the same in an extended position. 40
4. The construction set forth in claim 2, and an insulating disk supporting said pair of contacts. 45
5. The construction set forth in claim 2, and a central contact having connection with one of said pair of contacts. 50

In testimony whereof we affix our signatures in presence of two witnesses.

ELDEN R. PICKARD.
EDWIN C. PLATTS.
